UNITED STATES PATENT OFFICE.

ROBERT FFRENCH, OF STANMORE, NEAR SYDNEY, NEW SOUTH WALES, AUSTRALIA.

PROJECTILE

1,244,046.

Specification of Letters Patent. Patented Oct. 23, 1917.

Application filed July 20, 1917. Serial No. 181,681.

To all whom it may concern:

Be it known that I, ROBERT FFRENCH, a subject of the King of Great Britain, residing at Lydham, Newington Road, Stanmore, near Sydney, New South Wales, Australia, at present at Chelsea Hotel, New York city, in the county of New York and State of New York, have invented certain new and useful Improvements in and Relating to Projectiles, of which the following is a specification.

This invention relates to projectiles with more particular reference to those of the shrapnel type.

According to present practice shrapnel shells are charged with bullets of greater or less diameter and on the bursting of the explosive contained within the shell the charge is projected as a forward shower and only a very small proportion of the same comes direct to earth, so that the destructive properties generally of the shell are limited and the same is practically wholly ineffective in trenches or other positions protected from forward fire.

The object of the present invention is to devise an improved form of projectile of this character in which the charge is practically wholly effective inasmuch as the whole of it reaches the ground in such a manner as to produce destructive effects which are more intense than those procurable by means of the usual bullet charges while the improved projectile may also be effectively employed against trenches or other situations normally protected from forward fire.

According to my invention I provide a projectile of the shrapnel type but in which the charge comprises a plurality of disks, or sectors of disks of suitable metal.

The invention also comprises the improved projectiles hereinafter described or indicated.

The accompanying drawings illustrate several modes of carrying out the invention.

Figure 1 is a longitudinal sectional elevation showing one convenient form of projectile constructed in accordance with the invention.

Figs. 2 and 3 are respectively a plan and elevation showing one form of disk that may be employed with my improved shell.

Figs. 4 and 5 and 6 and 7 are similar views illustrating respectively two modified

forms of disk or sector that may be employed, and Fig. 8 is a perspective view illustrating thin and thick disks which may be used together.

In carrying my invention into effect in one convenient manner I provide a shell casing *a* which may be of the usual shrapnel type having a chamber for the bursting charge *b* in the lower portion of the shell while the fuse is arranged in the usual manner in the head *c*, the fuse and bursting charge being connected by means of a column of explosive extending longitudinally of the casing.

Within the casing and in front of the bursting charge I mount a number of disks or sectors *d* of cast or wrought iron or other suitable metal, the disks or sectors being provided with apertures *f* collectively forming a chamber for the dispersing explosive charge, and which may, if desired, be arranged slightly eccentric in relation to the disks to assist the latter to spread under the action of centrifugal force when released from the projectile. The disks may be all of one thickness, or as illustrated in Fig. 8 of the drawings I may arrange the same in pairs, each pair comprising a thick disk *d* and a thin disk *m* and in any modification of my invention the disks may be slit radially as shown at *g* (Fig. 4) or provided with slots as shown at *h* (Fig. 2) or angular cuts as shown at *i* (Fig. 2) or otherwise angularly cut or slotted to facilitate the breaking up of the disks when they strike against a hard object, care being taken, however, to leave sufficient metal around the central aperture *f* to insure the stability of the disk until it does so strike an object.

The slits or cuts may be arranged to be at right angles to the surface of the disks or sectors or they may be cut angularly thereto as shown at *h* and *i* so that the disks will when rotated in air in the direction in which the shell is rotated by the rifling of the gun operate to apply a backward tendency to the disks so that they will be projected more directly to earth on the bursting of the projectile.

In a further modification the sectors may be twisted slightly or the edges of the slits in the disks may be slightly bent upward as shown more clearly in Fig. 5 so that the disks or sectors when rotating in air will have a propeller-like action, the disks illus-

trated in Figs. 4 and 5 being especially suitable for shells to be used against aircraft.

When the disks are arranged in pairs, as shown in Fig. 8, the radial slits in the two disks forming a pair preferably register with one another so that the kerf edges of the thin disks *m* may fit within the openings in the thick disks *d* and such edges may be bent upward a little from the plane surface of the thick disks when both are interlocked. The thin disks are made of some resilient material and of such thickness as will permit their upset interlocked edges to lie snugly against the faces of the thicker disks when the disks are in position in the shell casing but when separated from the shell they will lie a small distance beyond the surface of the thick disk so that they will act as wind-guards and serve to scatter the disks in a backward direction.

In a projectile in accordance with the invention the disks or like members when separated from the shell on the bursting of the latter will be rotating owing to the previous rotation of the shell and on account of their weight and knife-like action due to the rotational movement, the disks or members have a much more highly destructive effect than shrapnel shot and, further, have the advantage that in whatever direction they are projected outward from the case they will still upon reaching the ground contain sufficient energy to insure destructive effects.

As contradistinctive from shrapnel shot which disperse in all directions the forward motion of the disks is owing to their flat surface arranged by the resistance imposed by the air so that the disks reach the ground in the locality of the explosion and not at some distance forward of it.

If the shell bursts on any considerable elevation the flight of the rotating disks will be more or less backward from the place of explosion and the destructive effect in trenches or other positions sheltered against forward fire will be greater than the effect of shrapnel shot.

When employing sectors of cast or other metal I may arrange the sectors *h* in pairs as shown in Figs. 6 and 7, the sectors being of such form and having their edges scarfed as is *l* in such a manner that when placed together their surfaces register with one another so that they form, as it were, one disk comprising two or more separable parts, each part of course being provided with its aperture *f* for the purpose above described. A further advantage of this form lies in the fact that as the material of each sector is not evenly distributed around its aperture *f*, the sectors are unbalanced about the aperture and hence their spreading is facilitated under the action of centrifugal force when the sectors leave the projectile.

If desired the disks or sectors or like members may be set in resin or other suitable substance to keep them in place within the shell casing.

It will be understood that the invention is not to be confined to any precise construction of shell casing that may be adopted nor to any particular fuses or bursting and dispersing charges that may be adopted for the projectile as these and other details may be suitably modified depending upon any particular practical requirements that the invention may be called on to fulfill.

What I claim and desire to secure by Letters Patent is

1. A projectile of the shrapnel type, comprising a casing, and a charge within said casing consisting of a plurality of substantially flat plate-like members constructed to retain their plate-like form when projected from said casing by the explosion of the projectile.

2. A projectile of the shrapnel type, comprising a casing, and a charge within said casing consisting of a plurality of members arranged transversely of said casing with their adjacent surfaces in contact, and constructed and arranged on the explosion of the projectile to be projected laterally of the line of flight without change of form.

3. A projectile of the shrapnel type, comprising a casing, a body of explosive at the rear thereof and a fuse at the forward end thereof, and a charge within the casing consisting entirely of a plurality of flat members arranged face to face and filling the portion of the casing in advance of said explosive, said members having central apertures forming a passage placing the fuse and explosive in communication, and being constructed to retain their original form when projected from the casing on the firing of the explosive.

4. A projectile as claimed in claim 1, wherein the plate-like members are arranged to rotate with said casing during flight thereof, and are constructed to move backwardly relatively to the line of flight of the projectile when projected from the casing on the explosion of the projectile.

5. A projectile as claimed in claim 1, wherein the plate-like members are arranged to rotate with said casing during flight thereof, and are constructed to move forwardly a short distance and then rearwardly relatively to the line of flight of the projectile when projected from the casing on the explosion of the projectile.

6. A projectile as claimed in claim 1, wherein the members are in the form of circular disks constructed to retain their disk form when projected from the casing.

7. A projectile as claimed in claim 1, wherein the members are in the form of disk sectors constructed to retain their origi-

nal sector form when projected from the casing.

8. A projectile as claimed in claim 7, wherein the disk sectors are arranged in 5 pairs to form a disk having its periphery in engagement with the interior of the casing, the adjacent edges of the two sectors being scarfed.

9. A projectile as claimed in claim 1, 10 wherein the plate like members are provided with slots to facilitate bursting of the members on striking an object.

10. A projectile of the shrapnel type, comprising a casing and a charge therein consisting of a plurality of disks arranged in 15 pairs, each pair comprising a thick disk having radial slots and a thin disk having por-

tions extending into the slots of the thick disk.

11. A projectile of the shrapnel type, comprising a casing and a charge therein consisting of a plurality of disks arranged in pairs, each pair comprising a thick disk having radial slots and a thin disk having portions extending into the slots of the thick 20 25 disk and arranged to project therefrom when the pair of disks is released from the casing.

In testimony whereof I affix my signature in presence of two witnesses.

ROBERT FFRENCH.
